PLEATING FOR SLIP COVERS AND
DRAPIERIES

Ernest J. Martens, St. Louis, Mo.

Application April 19, 1948, Serial No. 21,897

7 Claims. (Cl. 2—278)

1
This invention relates to the pleating of slip covers and draperies and in its more specific aspects is directed to a more efficient and expeditious means and method of forming pleats in slip covers or draperies.

The object of this invention is to provide novel means applicable to one of the edges of material from which slip covers or draperies are to be formed in conjunction with a member associated with said means which will enable quick uniform formation of pleating and the uniform spacing of groups of pleating on the slip covers or draperies.

Another object of the invention is the provision of a stiffening material to be applied to the slip covers or draperies in which the stiffening material has uniformly spaced members applied thereto or formed therein that cooperate with a draw member provided with uniformly spaced devices, such as notches, into which a selected number of the uniformly spaced members are collected to thereby form a group of uniformly sized pleats and to uniformly space the groups of pleats.

In the drawings:

Fig. 1 is a perspective view of an article of furniture provided with a cover portion which incorporates the invention.

Fig. 2 is a perspective view of a drapery incorporating the invention.

Fig. 3 is an enlarged view of one of the valances in Fig. 1 to which the invention is applied.

Fig. 4 is an elevational view of the reverse side of a structure incorporating one form of the invention.

Fig. 5 is a sectional view taken substantially along the line 5—5 of Fig. 4.

Fig. 6 is a sectional view taken substantially along the line 6—6 of Fig. 4.

Fig. 7 is a view showing the structure of Fig. 4 applied to fabric.

Fig. 8 is a sectional view taken substantially along the line 8—8 of Fig. 7.

Fig. 9 is a sectional view taken substantially along the line 9—9 of Fig. 7.

Fig. 10 is an elevational view of a modification of the structure shown in Fig. 4.

Fig. 11 is a sectional view taken substantially along the line 11—11 of Fig. 10.

Fig. 12 is a view of another modification of the structure shown in Fig. 4.

Fig. 13 is a sectional view taken substantially along the line 13—13 of Fig. 12.

Fig. 14 is a sectional view taken substantially along the line 14—14 of Fig. 12; and

Fig. 15 is a sectional view taken substantially along the line 15—15 of Fig. 12.

Referring now to Fig. 1 of the drawings, the

2
numeral 1 generally designates an article of upholstered furniture to which a slip cover has been applied that is trimmed with valances 2 and 3, each of which is constructed according to the teachings of this invention.

Referring to Figs. 3 to 9, the valance 3 is shown secured to the slip cover 4 that is formed from a suitable fabric. A strip of stiffening material 5, preferably crinoline, is sewed along its upper edge to the upper edge of the valance 3. This strip 5 has a plurality of pairs of slots 6, 6 cut therein which result in the formation of loops 7. These loops are uniformly spaced along the length of the strip 5. Inserted through the loop is a draw member 8 in which a series of uniformly spaced notches 9 are cut. These notches are made by severing a small portion from one of the folds of the member 8 to the fold line. When the notched draw member is inserted in the loops, three of the loops 7 are gathered into one of the notches 9 in draw member 8. This forms pleats 10 and 11, as shown in Figs. 3 and 9 in particular. These pleats, by reason of the spacing of notches 9 and loops 7, bear a definite mathematical relation one to the other and are, therefore, uniformly sized and spaced. The draw member will have a certain amount of overlap, as shown in Fig. 9. This may be eliminated by severing along the line 8' and then suitably securing the draw member to the strip 5 in any suitable manner. This results in a neater appearing piece of work.

When the pleats are formed they are folded flat against the valance material and a line of stitching is then applied to firmly hold them in position whereupon the valance may be installed on the slip cover material 4 by sewing or otherwise securing it thereto.

Fig. 10 shows a modified construction in which a strip of stiffening material 12, similar to strip 4, is sewed along its upper edge to one edge of the drape material 13. The loops in this illustration are staples 14 uniformly spaced along the length of the strip. Inserted in these staple loops is a draw member 15 having notches 16 cut therein, which are similarly formed and uniformly spaced as are notches 9 described above.

Fig. 12 shows still another modified form of the invention in which the strip of stiffening material 17 is a web of coarsely woven fabric made from a heavy yarn and is sewed at its upper edge to the material 18. Periodically along the length of the strip 17 one of the woof threads is lengthened to form loops 19. A draw member 20, provided with a plurality of spaced notches 21 and constructed in the same manner as draw member 8 above, is inserted through these loops 19.

The processing of the Figs. 10 and 12 dis-

3

closures is identical. A group of three successive staple loops 14 or loops 19 is gathered into one of the notches 16 or 21, thereby forming two pleats 22 and 23 which are folded back onto the material 13 or 18 and then sewed in position, as previously described in connection with Fig. 1.

When forming groups of three pleats, as used in draperies, any one of the three previously described stiffening strips may be employed. To illustrate, the mode of forming drapery pleats, the strip 24 (Figure 15) is sewed along one edge thereof to the upper edge of the material 25 and draw member 26 is inserted through uniformly spaced loops 28. Four of these loops are then gathered into one of the uniformly spaced notches 29 in draw member 26, thereby forming a group of three pleats 30, 30, 30. These project from the material 25 and are not sewed back onto it.

The crinoline from which the several draw members are formed has an inherent resiliency. This resilient quality is utilized in all forms illustrated and especially in the wire staple and woof thread loops by having the edges of each notch spring outwardly, as illustrated in Fig. 15, after the desired number of loops are gathered into each notch. The same action takes place in all forms illustrated but is shown only in the drapery illustration. The notch edges then prevent the loops moving relative to the draw members, thereby causing the plates to retain their shape and position.

From the foregoing it is believed that an expedient has been provided that will enable an unskilled person to successfully perform the pleating of slip cover valances and draperies so that the pleating will be uniformly sized as well as uniformly spaced by a proper selection of stiffening strips provided with loops suitably spaced, and a draw member likewise having suitably spaced notches into which a collection of a succession of loops are gathered to form a two pleat or a three pleat group, or any other number, with complete assurance that each group will be uniformly spaced and identical in size.

What I claim is:

1. A window drape comprising a piece of suitable fabric; a strip of stiffening material sewed to said fabric along one edge thereof; a draw member having resilient properties and provided with a plurality of uniformly spaced notches that are cut therein; and a plurality of draw member supporting means uniformly spaced along the length of and associated with said strip of stiffening material, uniformly spaced groups of said supporting means, each comprising an equally numbered succession of said means, each group being gathered into selected notches spaced periodically along the length of said member and held therein by the flared edges of each notch to thereby form a plurality of uniformly sized and spaced groups of pleats in the drapery.

2. A decorative article comprising a suitably shaped piece of fabric; a strip of relatively stiff material sewed to said fabric along one end thereof and having a plurality of uniformly spaced and sized loops formed therein; a draw member positioned in said loops and having a plurality of uniformly spaced and sized notches cut therein; and a plurality of uniformly spaced groups of loops, each group formed from a series of successive loops in said strip, each group being gathered in selected uniformly spaced notches for pleating said strip.

3. A decorative article comprising a suitably shaped piece of fabric; a strip of material sewed

4

to said fabric along one end thereof and having a plurality of uniformly spaced and sized loops cut therein; a draw member consisting of a folded strip of material and positioned in said loops and having a plurality of uniformly spaced and sized notches cut in one fold of said strip; and a plurality of uniformly spaced groups of loops, each group formed from a series of three successive loops in said strip, each group being gathered in selected uniformly spaced notches for pleating said strip.

4. A furniture slip cover comprising a suitably shaped piece of fabric; a strip of material sewed to said fabric and having a plurality of uniformly spaced loops associated therewith; and a draw member formed from a folded strip of material and in which a plurality of uniformly spaced and sized notches are cut in one fold of said strip, said strip of material having uniformly spaced groups of three successive loops assembled in selected uniformly spaced notches, the loops being held in said notches by the edges thereof for forming groups of pleats in said fabric.

5. A decorative article comprising a suitably shaped piece of fabric; a strip of relatively stiff material sewed to said fabric along one end thereof and having a plurality of uniformly spaced and sized loop means thereon; a draw member positioned in said loop means and having a plurality of uniformly spaced and sized notches cut therein; and a plurality of uniformly spaced and sized groups of loop means, each group formed from a series of four successive loop means in said strip, each group being gathered in selected uniformly spaced notches in said draw member for pleating said strip.

6. A decorative article comprising a suitably shaped piece of fabric; a strip of material sewed to said fabric along one edge and side thereof; a plurality of uniformly spaced staples secured to said strip of material; and a draw member arranged in said staples and provided with a plurality of uniformly spaced and sized notches, said staples being collected into uniformly spaced and sized groups thereof, each group comprising a series of successive staples, each group of staples being collected in selected uniformly spaced notches in said draw member for forming pleats in said fabric.

7. A decorative article comprising a suitably shaped piece of fabric; a strip of loosely knitted material sewed to said fabric along one edge thereof in which uniformly spaced threads extending transversely to the longitudinal axis of said strip are elongated for forming loops; and a draw member arranged in said loops and provided with a plurality of uniformly spaced and sized notches, said loops being collected into uniformly spaced groups thereof, each group comprising a series of successive loops, each group of loops being collected in selected uniformly spaced notches for forming pleats in said fabric.
